UNITED STATES PATENT OFFICE

2,599,876

WEAR PLATE FOR BRAKE HEADS

Theodore J. Sweger and Malcolm S. Johnson,
Chicago, Ill., assignors to Illinois Railway
Equipment Company, Chicago, Ill., a corpora-
tion of Illinois.

Application June 2, 1950, Serial No. 165,691

1 Claim. (Cl. 188—243)

The invention relates to a device adapted to present day standard brake heads, which may be easily applied to the shoe supporting and locking key receiving lug of the brake head to relieve the latter of wear and hence obviate the necessity of replacing the more or less expensive brake head; our improved device being such that its application may be readily accomplished.

Our improved wear plate comprises a unitary element stamped from blanks of sheet steel formed to overlie the shoe supporting lug of the brake head and provided with depending portions which utilize the key receiving slot or opening in the brake head lug whereby the device is secured to the head lug against accidental removal, while at the same time effecting a wedging action on the shoe holding key.

The aforementioned purposes and the advantages of our improved wear plate will all be readily comprehended from the following detailed description of the accompanying drawing wherein:

Figure 1 is a vertical section of the intermediate lug carrying portions of a brake head, shoe and shoe locking key, with our improved wear plate applied and shown in section and the initial position of the locking leg of the device shown in dotted lines.

Figure 2 is a perspective view of our improved wear plate; and

Figure 3 is a perspective view of the auxiliary member of the device which is adapted to be integrally applied to the main portion of the device.

The particular exemplification of our invention as shown in the drawing is formed from flat blanks of sheet steel of length and width sufficient to cover the top surface of shoe supporting lug 10 of a brake head of which a portion is shown at 11. The lug 10 supports the lug 12 of the shoe of which a portion is shown at 13; the shoe lug 12 being provided with the usual retaining steel strip 14. The head and shoe are held together by the conventional elongated key 15 which passes through the registering passages of the head and shoe lugs.

One member of the composite wear element is shown in Figure 2 formed to provide two flat faced lobes 16, 16 contoured at the rear edges to somewhat match a worn brake head lug, while the forward edges of the lobes are straight and flush with each other and united with each other by the connecting strip 17.

The connecting strip 17, at its inner or rear edge is cut or provided with a downwardly ex-

tending leg 18 which terminates in a forwardly bent toe 19; the blank inwardly or rearwardly of the leg 18 being open to provide passage for the shoe key 15.

Initially, the leg 18 slopes rearwardly as shown in dotted lines in Figure 1 and hence into the path of the shoe key 15 during insertion of the key from the top of the brake head. As is apparent, the key 15 will flex the leg 18 forwardly and cause the toe 19 to be forced beneath the head lug 10, while the leg 18 will remain in frictional bearing relation with the key and offer resistance to upward movement of the key.

In Figure 3, we illustrate the other or companion member of our composite wear element which also is formed from a blank of sheet steel to provide a pair of spaced lobes 20, 20, contoured similarly to the lobes 16, 16, except the lobes 20, 20, are connected at their inner or rear edges by a connecting strip 21.

The connecting strip 21 is cut to provide a downwardly bent tongue 22, integral with the rear edge of the connecting strip 21 and of length sufficient to afford sufficient bearing relation with the rear wall of the key way.

By reason of the length of the tongue 22, in conjunction with the length of the leg 18, a more or less holding relation with the head lug is effected and accidental displacement of the wear element prevented.

With the tongue 22, which is of comparative length, arranged in contact with the rear wall of the key way or passage in the head, and leg 18 flexed forwardly by insertion of the key 15, leg 18 is thereby positioned into close or contacting relation with the forward wall of the key way or passage and causes the toe to extend beneath the head lug as shown in full lines in Figure 1.

These conditions, in the event of withdrawal of the key for shoe replacement, will effect a holding relation between the wear element and brake head against accidental removal which can only be accomplished by forcing or prying the toe from beneath the head lug and bending the leg 18 rearwardly.

After the locking key 15 is driven in flexing the leg 18 forward and disposing toe 19 under the lower brake head lug, the leg 18 and tongue 22 will prevent rotary movement of the device about its horizontal axis and the wear element will be maintained in its proper position on the head lug.

The auxiliary or companion member 20, 20 preferably is intimately secured to the first men-

55

tioned member 16, 16 in any suitable manner, such as spot or plug welding through the holes shown at 23 in Figure 3.

Our improved wear element provides simplicity of application and its locking engagement with the head lug is automatically induced by driving the shoe holding key 15 in place, thus obviating the necessity for manually bending parts of the wear plate for securing a wear element in place.

We have described what we believe to be the simplest and best embodiment of our invention, but certain modifications are possible and may be made without, however, departing from the spirit of our invention as defined in the appended claim.

What we claim is:

In combination with a brake shoe having an apertured lug and a brake head having a brake shoe carrying lug with a key-receiving passage and a shoe locking key, a brake head wear element comprising a pair of matching members formed of flat sheet steel and intimately secured together, each plate formed to provide laterally spaced lobes united at one longitudinal edge by a tie strip, the tie strip of one member being at the forward longitudinal edge of the member and provided with a resilient downwardly bent rearwardly sloping leg intermediate the forward and rear edges of the element, substantially parallel with the forward edge of said one member, of length corresponding with the vertical thickness of the shoe-carrying brake head lug

and terminating in a forwardly disposed toe adapted to engage the lower face of the brake head shoe-carrying lug, while the tie strip of the other member is integral with the rear longitudinal edge of said other member and has a downwardly bent tongue at its rear edge, said leg and tongue being adapted to extend into the shoe key-receiving passage of said brake head shoe carrying lug, the leg of the first mentioned member being adapted to be flexed forwardly when the shoe key is driven into place and said toe forced forwardly beneath the head lug, thereby locking the wear element in place and holding said tongue of the second mentioned member in bearing relation with the rear wall of said key-receiving passage in the head lug whereby rotary movement of the element is prevented.
